IGNITER COIL MANUFACTURE

Henry W. Bilger and Karl T. Kessel, Meriden, Conn., assignors to The Cuno Engineering Corporation, Meriden, Conn., a corporation of Connecticut

Application August 20, 1937, Serial No. 160,046

6 Claims. (Cl. 29—155.5)

Our invention relates to a method and means for forming a resistance coil for cigar lighters and the like and especially coils of flat wire or ribbon wound in spiral form.

These coils are commonly formed by winding the ribbon on a hand operated, hand controlled or automatic machine in which the wire is fed onto a mandrel of proper diameter to form the central turn. The ribbon is then wound coil upon coil to form a spiral with all of the turns substantially in one plane. One disadvantage of this method is that it requires wire of a definite temper so that the coil is wound and released the normal spring of the wire is sufficient to cause the turns to space themselves from one another so as to prevent short circuiting. Another disadvantage of this method is that when the wire has sufficient temper to properly space itself when released after winding and the two ends of the coil are fixed to rigid conducting members in the assembled heating unit, the coils when heated, as in use, tend to shift somewhat and they become annealed into irregular relation with respect to one another. Some of the coils are too close and tend to short circuit and others are too far apart.

We have sought to provide a method of manufacture which will obviate these difficulties and produce a coil the turns of which will be uniformly spaced.

For this purpose we provide an arbor, the end of which is approximately conical but provided with steps arranged in the form of a combined helix and spiral. We use a dead soft or annealed wire or ribbon. Since this has no tendency to spring it takes and retains the size and spacing given it on the arbor and no shifting of coils takes place when heated in use. As these coils are usually flat or only slightly convex, we bring the helico spiral coil into the flat or substantially flat form by compressing it between dies. The resulting coil is a substantially flat spiral of regularity and uniformity and its form is held indefinitely in use.

Fig. 1 is an enlarged side view of the arbor showing a coil in section formed upon it.

Fig. 2 is an end view of the arbor.

Fig. 3 is a fragmentary section on a much enlarged scale showing the relation of adjacent turns upon the arbor.

Fig. 4 is a sectional view of a partially flattened coil.

Fig. 5 is an end view of an igniter element with the spiral coil.

Fig. 6 is a sectional view of the flattened coil

in the terminal or contact cup of an igniter element.

Fig. 7 is a perspective view of a fragment of the end of the ribbon to form the central part of the coil.

The mandrel or arbor 8 is formed of suitable metal and adapted to be rotated in a suitable type lathe etc. The end 9 of the arbor is in general conical and provided with a series of steps increasing in diameter spirally and progressing axially at the same time at a uniform pitch.

The ribbon 10 has its tip 11 bent over at an angle to fit in the slot 12 in the extreme end of the arbor. The central part 13 of the arbor may be formed separately from a rod and inserted and held adjustable in the body of the arbor. At each turn of the steps the radius increases by the amount 14 enough more than the thickness of the ribbon to allow for the space required between adjacent turns of the ribbon in the finished coil. The axial width 15 of each step is less than the width of the ribbon so that each turn overlaps the preceding turn as shown in Fig. 3. This makes it much easier to flatten or collapse the coil to the position of Figs. 4 and 6.

The ribbon or flat wire is made dead soft or highly annealed so that when the arbor is rotated the ribbon will lie smoothly upon the helico-spiral steps. As the wire has no resiliency or tendency to spring, it takes and retains its shape with the size and spacing of the turns determined by steps on the arbor on which it is wound.

If the coil is to be made more shallow axially it is a simple matter to shape it between dies to the slightly convex or concave form shown in Fig. 4.

The greatest number of cigar lighter coils are substantially flat as shown in Fig. 6 which form is fixed by setting the coil in a press or between flat dies.

These coils are used in shallow cups 16 such as shown in Figs. 5 and 6. The outer end of the coil is usually welded to the inner wall of the cup and the inner end of the coil is secured by welding, brazing, riveting, etc. in the central stud 17 of the igniter element.

As the wire ribbon is completely annealed before the coil is formed, no shifting of the coils takes place when the device is heated in use.

The coil produced in this way is much more uniform in turns and in spacing than those formed in any other known manner.

The use of a cup type receptacle of the general shape indicated on the drawing is of advantage

in its assistance in holding the coil in position before the welding operation. As shown in the drawing the radial separation of the convolutions of the finished coil is substantially uniform and 5 not greater than about twice the thickness of the metal ribbon.

We claim:

- 10 1. The method of making an igniter coil which comprises winding a flat ribbon into a helico-spiral form with each convolution partially overlapping the preceding convolution in an axial direction and spaced radially therefrom and then pressing and thereby permanently setting all convolutions in a substantially common plane.
- 15 2. The method of forming an igniter coil which comprises winding a dead soft ribbon of metal upon an arbor having a helicoidal step, the width of the step axially of the arbor being less than the width of the ribbon and the height of the 20 step radially of the arbor axis being greater than the thickness of the ribbon and then pressing and thereby permanently setting all of the convolutions of the coil into approximately the same general plane.
- 25 3. The method of forming a spiral resistance coil having a plurality of spaced convolutions, which comprises winding a soft flat strip of resistance wire on a stepped conical arbor beginning near the axis and gradually increasing in 30 diameter, each succeeding convolution being spaced from but partially overlapping the next inner convolution, then removing the coil from the arbor and compressing the coil between dies and thereby permanently setting the convolutions into a substantially common plane.
- 35 4. The process of making an ignition coil for

a cigar lighter which comprises wrapping substantially flat soft electric resistance metal onto an arbor having flat steps and forming a conical helical coil with the convolutions substantially equally spaced radially not substantially more than about twice the thickness of said metal, removing the coil from said arbor by relative translation therebetween, shortening the axial length of said coil by pressure applied in the general direction of the coil axis. 5

10 5. The process of forming a cigar lighter heating coil which comprises winding substantially flat dead soft electric resistance ribbon on an arbor provided with substantially flat steps of approximately uniform height and of roughly 15 not more than about twice the thickness of the ribbon to form a conical helical coil with the convolutions radially spaced, removing the entire coil from the arbor without substantially expanding or contracting the convolutions, by relative translation between the arbor and all convolutions of the coil. 20

25 6. The process of forming a generally spiral heating coil for a cigar lighter which includes winding soft flat electric resistance metal into a conical helical form with the convolutions radially spaced, compressing the coil in the general direction of its axis to very substantially shorten the axial length of the coil by pressure applied to the side edges of the metal until the side edges 30 of the convolutions and the inner end of the metal are substantially aligned from the center of the coil outwardly. 35
